UNITED STATES PATENT OFFICE.

EDWIN R. EVANS AND CARL M. TICHENOR, OF DETROIT, MICHIGAN.

OIL BURNER.

Application filed July 23, 1923. Serial No. 653,267.

This invention relates to heating apparatus and refers more particularly to liquid fuel burners for stoves or furnaces.

An object of the invention is to provide a practical and efficient apparatus which is capable of completely atomizing heavy liquid fuels such as crude oil, the heavier distillates and residuum oils and mixing the atomized fuel with air to form a mixture that can 10 be completely burned without the formation of smoke.

Another object is to provide a simple apparatus in which the liquid fuel reservoir may be raised or lowered relative to the burner 15 for varying the level of the fuel in the burner.

With the above and other objects in view, the invention consists in certain novel features of construction, combination and arrangement of parts as will be more fully described and particularly pointed out in the appended claims.

In the accompanying drawings:—

Figure 1 is a side elevation of an apparatus embodying my invention and showing parts 25 in section;

Figure 2 is a top plan view thereof;

Figure 3 is an end view thereof.

Referring now to the drawings in which like characters of reference designate corresponding parts throughout the several views, the numeral 1 designates an upright frame 30 for supporting an oil burner 2 which preferably is provided with an open top receptacle 3 for oil, and a discharge cup 4 that preferably receives its supply of oil through a vertical tube 5 which is carried by the hub 6 of the cup and which preferably extends downwardly into the receptacle 3. The receptacle is preferably formed integral with 35 a spider 7 that is detachably secured to the frame 1 while the cup 4 is preferably rotatable within an annular upstanding flange 8 of a horizontal ring 9 that is also detachably secured to the frame 1.

If desired, the ring 9 may be provided with 45 extensions 10 for engagement with suitable supports (not shown) in the fire box of a furnace. The hub 6 of the cup is preferably fixed upon a vertical shaft 11 which is driven 50 by a suitable electric motor 12 detachably mounted upon the frame 1 at the lower end thereof. A thermostat (not shown) preferably controls the operation of the motor. The shaft 11 is preferably rotatably mounted 55 in a vertical central tubular portion 13 of the receptacle 3 and is preferably detachably

secured to a motor driven shaft 14 by means of a suitable coupling member 15.

In order that the cup 4 will rotate easily, we preferably provide antifriction bearings 60 between the hub 6 and the upper end of the tubular portion 13 of the receptacle. The cup 4 is substantially frusto-conical in form and is preferably provided at its lower end with a trough 17 that is adapted to catch any 65 oil draining down the walls thereof. The trough 17 is preferably spaced from the hub 6 of the cup to provide an opening through which air may be drawn upwardly by a series of radially extending vanes 18, preferably 70 formed integral with the lower face of a cover 19 which is preferably secured to the upper end of the shaft 11 and which is preferably spaced from the outwardly flaring upper end 20 of the cup to provide an annular discharge orifice 21.

With the construction thus far described, it will be apparent that rotation of the cup 4 will cause the tube 5 to travel in a circular path in the receptacle 3 and thus to pick up 80 oil therefrom. As a result of the centrifugal force, the oil discharged from the tube 5 will be thrown toward the walls of the cup and will be mixed with air drawn upwardly through the opening in the bottom of the 85 cup. This mixture in the form of vapor will then be discharged through the orifice 21 and will burn at the point indicated by the lines 23 in the form of an annulus, the vapor mixture being ignited by a suitable pilot light 90 (not shown).

To prevent the oil from splashing out of the receptacle 3 when the tube 5 travels around therein, we preferably provide an annular flange 24 which is preferably formed 95 integral with the receptacle 3 adjacent to the open top thereof. An annular skirt 25 is also preferably formed integral with the hub 6 of the cup and preferably extends into the open end of the receptacle 3 above the 100 flange 24.

The oil reservoir is designated generally by the numeral 25 and preferably consists of an inverted bottle 26 having a neck 27 registering with an upstanding tubular extension 28 of a container 29 which is preferably provided with lateral extensions 30 having apertured portions 31 at the ends thereof threaded upon a plurality of standards 32 and which is preferably connected to the receptacle 3 of the burner by means of a suitable conduit 33. The top of the container 105

110

29 is preferably provided with an opening 34 which receives an air tube 35, while the bottom of the container is preferably provided with a draining opening 36 that is preferably closed by means of a suitable plug 37.

5 A cap 38 is preferably detachably secured to a collar 39 fixed upon the neck 27 of the bottle and is preferably provided with a discharge nozzle 40 that delivers oil into the container 29 to the depth indicated, the depth being determined by the position of the discharge nozzle. The cap 38 is preferably provided with a cup-shaped portion 41 that projects into the tubular extension 28 of the container and thus prevents the neck of the bottle moving accidentally out of registration with the tubular extension 28, while a plurality of sleeves 42 preferably surround the standards 32 above the lateral extensions 30 10 of the container and are preferably secured at their upper ends to a ring or band 43 which preferably surrounds the bottle.

15 The size of the flame in the burner is varied by the amount of oil in the receptacle 3, and the oil supplied in this receptacle is varied by the position of the bottle 26. Thus, when the standards 32 are rotated by engagement of a suitable tool (not shown) with the hexagonal bases 44 thereof, the container 29, sleeves 42 and bottle 26 will be moved simultaneously vertically with respect to the burner, and as a result the level of the liquid fuel in the receptacle 3 will be varied.

20 While it is believed that from the foregoing description, the nature and advantages of the invention will be readily apparent, we desire to have it understood that we do not limit ourselves to what is herein shown and described and that such changes may be resorted to when desired, as fall within the scope of what is claimed.

25 What we claim as our invention is:

1. The combination with a hollow rotatable discharge member, of a receptacle for liquid fuel beneath said member, means for effecting a flow of air through said member, driving means for rotating said member and means movable in an orbit about said driving means for transferring fuel from said receptacle to said member.

2. In an apparatus of the class described, a burner having a receptacle for liquid fuel and a discharge cup, means moving in an orbit for supplying fuel from the receptacle to the cup, and a motor beneath the receptacle for rotating the cup to discharge the contents thereof.

3. In an apparatus of the class described, a burner having an open top receptacle for liquid fuel and a rotatable discharge cup adapted to receive fuel from the receptacle, a member carried by the cup laterally offset from the axis thereof and extending into the receptacle for conveying fuel from the receptacle to the cup, means for rotating the

cup to cause said member to move around in the receptacle and to transfer fuel from the receptacle to the cup, and means for preventing the fuel from splashing out of the receptacle when said member moves around therein.

4. In an apparatus of the class described, a burner having a receptacle for liquid fuel and a discharge cup, means for supplying fuel from the receptacle to the cup, and means below the receptacle for rotating said cup and fuel supply means.

5. In apparatus of the character described, a receptacle for fuel, a rotatable discharge member located above said receptacle, means for effecting a flow of air through said member, means below said receptacle extending upwardly therethrough for rotating said discharge member and means moving in an orbit about the axis of said discharge member for conducting fuel thereto from said receptacle.

6. In an apparatus of the class described, an open top receptacle for liquid fuel, a rotatable discharge member disposed above said receptacle, means for effecting a flow of air through said discharge member, means adapted to travel around in said receptacle for transferring fuel to said discharge member, and means for preventing fuel splashing out of said receptacle.

7. In an apparatus of the class described, a burner having a receptacle for liquid fuel and a rotatable discharge member, means located below said receptacle and having a shaft extending vertically therethrough for driving said discharge member, and means to one side of the driving shaft rotatable with said member adapted to travel around the axis of rotation of said member and in the receptacle for conveying fuel from the receptacle to the discharge member.

8. In an oil burner structure, a receptacle in which fuel is maintained at a substantially predetermined level, a rotatable burner cup arranged above said receptacle, a motor arranged below said receptacle with the shaft thereof extending upwardly centrally through said receptacle and connected to said burner cup, and means carried by said cup movable in an orbital path about said shaft adapted to skim the surface of said fuel for supplying fuel to said cup.

9. An oil burner of substantially the character described comprising in combination, a receptacle containing fuel, a rotatable cup-like member located above said receptacle, a motor below said receptacle, a shaft driven by said motor extending upwardly through said receptacle for rotating said cup-like member and means moving in an orbital path about said shaft adapted to dip into the fuel in said receptacle for conducting fuel therefrom into said cup-like member.

10. An oil burner of substantially the character described comprising in combination, a

- receptacle containing fuel, a rotatable burner cup located above said receptacle, a motor below said receptacle, a shaft driven by said motor extending upwardly through said 5 receptacle for rotating said burner cup and means carried by said burner cup and moving in an orbital path about said shaft adapted to dip into the fuel in said receptacle for conducting fuel therefrom into said member.
- 10 11. In an oil burner structure, the combination with an oil receptacle provided with a vertical rotatable shaft, of a burner cup secured to the upper end of said shaft and having a cap disposed thereon to provide an annular burner orifice, a tube extending from the bottom of said burner cup and provided with a tip arranged to skim the surface of the oil in said receptacle and to lift a spray therefrom, said tube extending into said burner 15 cup, and power means for rotating said vertical shaft.
12. In an oil burner structure, the combination with an oil receptacle provided with a vertical rotatable shaft, of a burner cup secured to the upper end of said shaft and having a cap disposed thereon to provide a nozzle 20 orifice, said cup being provided with skirted means depending into said receptacle and in- teriorly provided with oil-lifting means, said oil-lifting means being provided with an oil entrance to said burner cup, and power means for rotating said cup. 30
13. In an oil burning structure, the combination with an oil receptacle, of a burner cup having air openings in its under side disposed rotatively above said casing, means on said cup displaced from the axis thereof and projecting into said casing adapted for lifting oil when said cup is rotated, said oil lifting means being provided with an oil entrance to 35 said burner cup, additional means associated with said cup for drawing air through said openings when said cup is rotated, and power means for rotating said cup. 40
14. In an oil burner structure, the combination with a chambered oil well casing, of means for supplying oil thereto, a burner cup rotatably disposed above said casing and provided with an oil pick-tube extending into 45 said casing and arranged to lift oil therefrom, means for supplying air for combustion, and power means for rotating said burner cup. 50

In testimony whereof we affix our signatures.

EDWIN R. EVANS.
CARL M. TICHENOR.
